(57) **CLAIM**

The ornamental design for fastener for a card edge connector, as shown and described.

DESCRIPTION

FIG. 1 is a perspective view of fastener for a card edge connector showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a plan view in use wherein the fastener is connected to the connector; and,

FIG. 9 is a plan view in use wherein the fastener is disconnected from the connector.

The broken line showing of the environment is for illustrative purpose only and forms not part of the claimed design.
